Patented Dec. 17, 1968

212,993

HAIR DRYER

Austin E. Cox, Rustic Hills, Ohio, assignor to Dominion
Electric Corporation, a corporation of Ohio

Filed Oct. 24, 1967, Ser. No. 9,138

Term of patent 14 years

(Cl. D86—10)

Fig. 1

Fig. 2

Fig.3

Fig. 4

Fig. 5

Fig. 6

Fig. 7

Fig. 8

I claim:

The ornamental design for a hair dryer, substantially as shown and described.
